United States Patent Office

Des. 193,693
Patented Sept. 25, 1962

193,693

STEREOSCOPIC CAMERA

Rudolf Steineck, P.O. Box 8, Lugano-
Cassarate, Switzerland

Filed Sept. 1, 1961, Ser. No. 66,591

Term of patent 7 years

(Cl. D61—1)

FIG. 1

FIG. 2

FIG. 3

FIG. 1 is a front-perspective view of a stereoscopic camera showing my new design;

FIG. 2 is a top-plan view thereof; and

FIG. 3 is a rear-perspective view thereof.

The bottom of the stereoscopic camera is plain and unornamented.

I claim:

The ornamental design for the stereoscopic camera, as shown and described.
